 Ohio

Application December 18, 1937, Serial No. 180,607

10 Claims. (Cl. 68—54)

This invention relates to new and useful improvements in apparatus for washing clothes of the general type illustrated in my Reissue Patent No. 20,313 which was issued on March 20, 1937.

5 The present invention constitutes a continuation-in-part of my application Serial No. 701,853 filed on December 11, 1933, for Laundry machine, issued on May 10, 1938, as Patent No. 2,116,759, and it also has reference to certain of the improvements in agitators shown in my copending 10 application Serial No. 80,252 which was filed on May 18, 1936, for Washing machine.

The invention has for its objects the provision of an agitator of the general type described in my 15 above-mentioned patent embodying certain improvements for increasing the washing efficiency of the agitator whereby the same is adapted to thoroughly cleanse the clothes through the combined action of vigorously working and circulating the clothes about in the washing fluid while at the same time subjecting them to the action 20 of rubbing and scrubbing surfaces of relatively large area and forcibly causing the washing fluid to pass through the pores of the fabric of the clothes.

These and other objects of the invention will become more apparent and better understood after consideration has been given to the following detailed description of the invention taken in 30 connection with the drawings which show, merely by way of illustration, structure adapted for carrying out the objects of the invention.

In the drawings, Figure 1 is a side elevational view of an agitator, illustrative of one embodiment of the invention; Figure 2 is a plan view of the agitator shown in Figure 1; Figures 3 and 4 are detail sectional views to illustrate the construction of the agitator blades, such views being taken on lines 3—3 and 4—4 respectively of Figure 1; Figure 5 is a detail sectional view of the base and a portion of the center post of the agitator taken on line 5—5, Figure 2; Figure 6 is an enlarged detail sectional view of a portion of one of the blades of the agitator taken on line 6—6, Figure 1; Figure 7 is a side elevational view of a modified form of agitator in which two blades similar to those shown on the agitator in Figure 1 are employed; Figure 8 is a plan view of the agitator shown in Figure 7, the agitator having been 40 turned approximately forty-five degrees in a clockwise direction from the position shown in Figure 7; Figure 9 is a side elevational view of another modified form of agitator in place in a washing machine; Figure 10 is a plan view of the agitator shown in Figure 9; and Figure 11 is an

enlarged detail sectional view taken on line 11—11, Figure 9, of a portion of one of the blades of the agitator shown in Figures 9 and 10.

This invention is concerned primarily with the so-called gyrator type of washing machine in 5 which the fluid and clothes are circulated by means of a dolly or agitator which is adapted to be oscillated about a vertical axis in the washing machine tub for the purpose of vigorously agitating the clothes and washing fluid in the 10 tub during the operation of the machine.

In the form of the invention illustrated in Figure 1, there is shown a dolly or agitator comprising a base portion 1 and a centrally disposed center post 2 extending upwardly therefrom. A 15 plurality of similarly formed blades 3, 4 and 5 project upwardly from the base and outwardly from the center post, as shown in the drawings. These blades are warped or wound about the axis of the agitator in a counter-clockwise direction and as is shown best in Figure 1, the width or surface area of each blade is somewhat decreased at the upper portion thereof where each of the blades is provided with a substantially vertical section 3a, 4a and 5a respectively for the 20 different blades.

The intermediate portion 3b, 4b and 5b of the 25 respective blades is inclined with respect to the horizontal. The lower portion 3c, 4c and 5c of the respective blades is curved or cupped somewhat so as to provide a convex area on one side and a concave area on the other side of this portion of each of the blades. For purposes of convenience, the convex area may be stated as 30 being located on the upper or forward face of each blade.

When viewed from above, the outside edges of the blades of the agitator wind about the axis of the agitator in a counter-clockwise direction 35 from the bottom to the top thereof. The innermost portion of each blade merges with the centerpost 2 along a substantially straight, vertical line. The lowermost portion of each blade is joined to the base 1 on a curved line, the convex 40 side of which faces in a clockwise direction.

The opposite faces of each of the blades are 45 provided with a series of ribs or corrugations 6 which extend lengthwise of the blades and provide rubbing or scrubbing projections thereon. 50 In addition to the lengthwise extending corrugations, the blades of the agitator are also provided with widthwise or radially extending corrugations or ribs 7 on what has been termed the upper or top face of the blades. Perforations or aper- 55

tures 8 are also provided in the areas between the ribs or corrugations of the blades of the agitator.

In the circulation of the fluid and clothes, there is a general movement of the same across the base 1 of the agitator and as a further means for enhancing the washing action, the base is provided with a series of annular ribs or corrugations 10. Holes 11 are provided in the channels defined between each of these ribs or corrugations 10 for the same purpose as for the holes 8 of the blades. The holes 11 and the ribs 10 cooperate to flex and bend the clothes in much the same manner as for the holes 8 and ribs 6 and 7 of the blades, as will be described later herein.

15 The underside of the agitator is provided with a tapered prismatic opening 12 for the reception of an agitator driving shaft (not shown) having an end of complementary outline. The agitator is secured to the agitator shaft by any suitable 20 means, such as, an elongated screw (not shown), the head of which seats in the topmost portion of the agitator and the threaded portion of which is received in the agitator driving shaft.

25 The apertures 8 and the corrugations 6 and 7 greatly enhance the washing speed and efficiency of this agitator. Considering these features of construction separately, the ribs or corrugations which are formed on the blades of the agitator rub and scrub the clothes as they are moved and 30 contacted by the agitator and the perforations assist in causing the flow of washing fluid through the pores of the fabric of the goods being laundered while at the same time they cause such goods to be drawn into close contact with the 35 blades of the agitator where they are rubbed and scrubbed during the operation of the machine.

40 The combined use of the perforations and corrugations mutually contribute to enhance the advantages each of these features possess when used separately. For example: the corrugations serve to define shallow depressions about each aperture to direct and facilitate the movement of water therethrough and the movement of liquid through the perforations tends to draw the articles against the corrugations where they are 45 rubbed and scrubbed.

50 In the more usual construction of agitator where a vertically disposed, imperforate blade is used, the fluid and clothes move by the blades of the agitator without any substantial rubbing contact, as described in Snyder Patent No. 1,866,779. In the 55 present construction, however, because of the combined action of the perforations and the rubbing projections, there is a strong tendency for the clothes to adhere to the blades during their oscillation and the washing action of the agitator is measurably increased over a smooth imperforate blade, or a smooth blade with perforations or a corrugated imperforate blade. 60 The inclination of the blades also promotes the washing efficiency of the agitator by providing a relatively large surface area for contact with the clothes without, however, overloading the driving motor of the machine.

65 The flexing and bending of the clothes is also materially promoted by locating the perforations in depressed areas of the blades of the agitator. Thus when a piece of fabric is drawn toward one or the other of the holes 8 of the blades, it is 70 flexed and bent over the ribs and corrugations surrounding such hole.

75 The modification of the invention illustrated in Figures 7 and 8, shows the manner of adapting the form of blade construction illustrated in Figure 1 to a two-vaned agitator. In this modi-

fication of the invention, the agitator comprises a base 20, a center post formed from a frusto-conical bottom section 29 and a substantially cylindrical section 21 extending upwardly therefrom as in the case of the agitator shown in Figure 1 and a pair of oppositely disposed, curved and inclined blades 22 and 23 which are substantially the same as the blades of the agitator shown in Figure 1.

The blades of the agitator are provided with 10 lengthwise extending ribs 24 and widthwise extending ribs 25 between which holes 26 are formed. The base 20 has a plurality of annular ribs 27 between which holes 28 are provided. Each of the blades is provided with a substantially vertical section 22a and 23a respectively, an inclined intermediate portion 22b and 23b respectively, and curved or cupped lower portion 22c and 23c respectively, all as in the case of the agitator first described. The base of this agitator is provided with a prismatic socket (not shown) inside the frusto-conical section 29 of the center post for the reception of an agitator shaft (not shown). The blade portions 22a and 23a 25 22c and 23c of the present agitator and the blade portions 3a, 4a and 5a, and 3c, 4c and 5c of the agitator first described are cupped somewhat after the manner disclosed in my earlier patent.

30 The modified form of agitator shown in Figures 7 and 8 operates in substantially the same manner as the agitator shown in Figures 1 to 6 and it is intended for use where the matter of cost is an important factor as this agitator is somewhat less expensive to make and while its washing speed may be slightly less than that of the three-bladed agitator, it provides a very acceptable 35 type of agitator which is particularly useful for washing machines in the lower price ranges.

35 During the operation of the agitators shown in Figures 1 to 8, there is a relative movement of 40 the articles being washed upwardly and downwardly and inwardly and outwardly in contact with the faces of the blades of the agitator whereby the clothes are rubbed and scrubbed by both the lengthwise and the widthwise extending 45 ribs or corrugations of the individual blades of the agitator, and in this manner, the clothes are cleansed through the joint action of rubbing contact with the blades and flexing and bending as they are worked upon during the operation of the 50 agitator.

55 In addition to the foregoing, the perforations of the agitator greatly promote the movement of water through the pores of the fabric of the clothes whereby the same are quickly and thoroughly cleansed during the operation of the machine and a well-defined washing action takes place throughout the entire contents of the tub from top to bottom and from the center to the outermost portions of the tub. The stepped construction of the edge of the upper portion 2a, 3a and 4a and 22a and 23a of the blades assists in the washing action by reason of its wavy outline and this arrangement also has the very important function of preventing the clothes from sliding up upon this portion of the blades and becoming hooked over the top of the agitator.

60 The washing action of the aforesaid agitators may be likened to a combination of washing actions of a gyrator washing machine, a cylinder 65 washing machine and a vacuum cup washing machine. For example: in the operation of this device, the turbulent agitation of the gyrator washer is reproduced to a very high degree; the close contact with the rubbing and scrubbing 70 75

surfaces of a cylinder machine is reproduced in a large measure; and the action of a vacuum-cup machine in forcing the washing fluid back and forth through the pores of the fabric of the 5 articles being washed, is also achieved.

In Figure 9, there is shown a modified form of agitator in connection with a washing machine tub or vat and suitable gearing for oscillating the agitator. In this modification of the 10 invention, the agitator is located in a tub 30 beneath which there is located a gear case 31 for housing suitable mechanism for operating the agitator. This mechanism includes an agitator driving shaft 32 having a pinion 33 fixed at its 15 lowermost end.

The pinion 33 is driven with a reversely rotary movement by means of a reciprocating rack bar 34 which is driven by any suitable mechanism (not shown) as is customary in machines of the 20 type to which this invention relates. The upper end of the agitator shaft 32 is provided with a tapered prismatic head 35 which is received in a complementary recess formed in the portion of the agitator defined by the frusto-conical center post section 36.

The agitator disclosed in this modification of the invention comprises a base portion 37 and a centrally disposed, substantially cylindrical section 38 which extends upwardly from the frusto-conical section 37 and these two elements combine to form a center post for the agitator. Vertically disposed blades 40, 41 and 42 extend upwardly from the base and outwardly from the center post of the agitator. The agitator blades 30 are of grid-like conformation and they comprise a series of upright parallel bars 43 and a series of radially extending or width-wise extending cross bars 44. The bars 43 are of slightly larger 35 diameter than are the bars 44 and together these bars define an impeller blade of highly perforate construction which causes the clothes to strongly adhere to the blade surfaces during the operation of the machine and in this manner, the clothes are rubbed and scrubbed while at the same time washing fluid is forced through the 40 pores of the fabric of the goods.

In the operation of the agitator shown in Figures 9 to 11, the movement of the washing fluid and clothes is largely in horizontal paths toward 45 and from the center of the tub and back and forth around the blades of the agitator and in so moving, the clothes are subjected to a rubbing and scrubbing action, a forcing of washing fluid through the pores of the fabrics being washed, and a bending and flexing similar to that described in connection with the earlier forms of 50 the invention.

The washing action at the top surface level of the liquid is slightly less for the agitators 55 shown in Figures 1 to 8 than it is for the agitators described in my cited reissue patent because of the reduction in the blade area at the upper portion of the agitator. The present construction eliminates the splashing of water out 60 of the tub which occasionally occurred in the use of my prior patented agitators and the new washing features of the present agitators more than compensate for this slight reduction in the agitation at the upper portion of the tub.

70 It is important to note that the general circulatory movements of the fluid and clothes which occur during the operation of the agitators shown in Figures 1 to 8 take place at a relatively slow speed so that each of the individual 75 articles of a batch of clothing will be subjected

to the rubbing and scrubbing and flexing and bending action of the blades of the agitator for an appreciable time before they move away from the immediate zone of action of such blades.

The various forms of agitators disclosed herein, may be mounted in a washing machine tub for oscillation about a substantially vertical axis, as illustrated in Figure 9 of the drawings, and the amplitude of agitation may be in the neighborhood of 200 degrees more or less. In the operation of the machine, the normal surface level of cleansing fluid is at or slightly above or slightly below the top of the agitator, the preferred level being about an inch below the top of the agitator although the device will operate with a 10 lesser or a greater amount of water than that mentioned. Where but a few number of articles are to be washed, the water level may be lowered 15 very considerably from the levels mentioned.

The foregoing description and the accompanying drawings to which it relates, describes what might be termed the preferred modes of practicing the invention.

Having thus described my invention what I claim is:

1. In a device of the type described, a tub having a normal surface level of cleansing fluid, an oscillatable agitator mounted in said tub, said agitator comprising a base portion, a central portion projecting upwardly therefrom, a plurality of upstanding blades projecting from said base and central portions, said blades being inclined with respect to the horizontal and having rubbing and scrubbing corrugations extending lengthwise of the blades and other rubbing and 30 scrubbing projections extending radially of the blades between said corrugations and openings for the passage of liquid in areas defined between said corrugations and projections, and means for oscillating said agitator.

2. A washing machine comprising, a tub for washing fluid and clothes, an agitator mounted in said tub for movement about a vertical axis, and means for oscillating said agitator, said agitator comprising a body portion and a projecting 45 impeller blade extending upwardly throughout the entire height of the tub contents and for a slight distance thereabove, the width of said blade abruptly decreasing at its uppermost portion, such portion being of stepped construction to 50 prevent the clothes being washed from sliding up and over the top of the blade and becoming suspended thereat above the surface level of the washing fluid.

3. A washing machine comprising, a tub for 55 washing fluid and clothes, an agitator mounted in said tub for movement about a vertical axis, and means for oscillating said agitator, said agitator comprising a body portion and a projecting impeller blade extending upwardly throughout the 60 entire height of the tub contents and for a slight distance thereabove, said blade being inclined with respect to the horizontal with the width of the blade decreasing as its uppermost portion is approached, such portion being of stepped construction to prevent the clothes being washed from sliding up and over the top of the blade and becoming suspended thereat above the surface level of the washing fluid.

4. A washing machine comprising, a tub for 70 washing fluid and clothes, an agitator mounted in said tub for movement about a vertical axis, and means for oscillating said agitator, said agitator comprising a body portion and a plurality of projecting impeller blades extending upward- 75

ly throughout substantially the entire height of the tub contents, said blades being of warped configuration with the width of each of the blades abruptly decreasing at its uppermost portion, such portion being of stepped construction to prevent the clothes being washed from sliding up and over the top of the blade and becoming suspended over the top of the agitator.

5. In a device of the type described, a tub having a normal surface level of cleansing fluid, an oscillatable agitator mounted in said tub, said agitator comprising a body portion, a plurality of upstanding blades projecting from said body portion, said blades being inclined with respect to the horizontal and having rubbing and scrubbing corrugations extending lengthwise of the blades and other rubbing and scrubbing projections extending radially of the blades between said corrugations and openings for the passage of liquid in the areas defined between said corrugations and projections and means for oscillating said agitator.

6. In a device of the type described, a tub having a normal surface level of cleansing fluid, an oscillatable agitator mounted in said tub, said agitator comprising a base portion, a central portion projecting upwardly therefrom, a plurality of upstanding blades projecting from said base and central portions, said blades being inclined with respect to the horizontal and having rubbing and scrubbing corrugations extending lengthwise of the blades and other rubbing and scrubbing projections extending radially of the blades between said corrugations and openings for the passage of liquid in the areas defined between said corrugations and projections, said base portion also having rubbing and scrubbing projections for facilitating the cleansing operation, and means for oscillating said agitator.

40 7. In a device of the type described, a tub having a normal surface level of cleansing fluid, an oscillatable agitator mounted in said tub, said agitator comprising a base portion, a central portion projecting upwardly therefrom, a plurality of upstanding blades projecting from said base and central portions, said blades being inclined with respect to the horizontal and having rubbing and scrubbing corrugations extending lengthwise of the blades and other rubbing and 45 scrubbing projections extending radially of the blades between said corrugations and openings for the passage of liquid in the areas defined between said corrugations and projections, said base portion having circumferentially disposed corrugations with openings therebetween for rubbing

55 and scrubbing the articles being washed, and means for oscillating said agitator.

8. An agitator adapted to oscillate about a vertical axis comprising a base, a central portion rising centrally from said base, a plurality of 5 blades joined to said central portion and base, each of said blades having its outer edge portion spirally curved to provide a blade area inclined with respect to the base, each of said blades provided with spiral corrugations along its outer edge 10 portion and a smooth imperforate portion intermediate said corrugations and the central portion of the agitator, said smooth imperforate portion effecting a radially outward movement of the clothes and water upon agitator oscillation and 15 said corrugations effecting a scrubbing of the clothes as the clothes traverse the last-named portion during their outward movement.

9. An agitator adapted to oscillate about a vertical axis comprising a base, a central portion 20 rising centrally from said base, a plurality of blades joined to said central portion and base, each of said blades having its outer edge portion in the form of a spiral to provide a blade area curved with respect to the base, each of said 25 blades provided with a perforated portion along its outer edge portion and a smooth imperforate portion intermediate said perforated portion and the central portion of the agitator, said smooth imperforate portion effecting a radially outward 30 movement of the clothes and water upon agitator oscillation and said perforated portion effecting a rubbing of the clothes as the clothes traverse the last-named portion during their outward movement.

35 10. An agitator adapted to oscillate about a vertical axis comprising a base, a central portion rising centrally from said base, a plurality of blades joined to said central portion and base, each of said blades having its outer edge portion 40 curved to provide a blade area inclined with respect to the base, each of said blades provided with a corrugated portion having holes between the corrugations along its outer, curved edge and a smooth imperforate portion intermediate said 45 perforated, corrugated portion and the central portion of the agitator, said smooth imperforate portion effecting a radially outward movement of the clothes and water upon agitator oscillation, and said perforated, corrugated portion effecting 50 a retarding, rubbing action on the clothes as the clothes traverse said perforated, corrugated portion during their outward movement.

JAMES B. KIRBY.
